STOKER MECHANISM

Chester W. Bros, Edina, Minn., assignor to Wm. Bros Boiler & Manufacturing Co., Minneapolis, Minn., a corporation of Minnesota

Application January 24, 1949, Serial No. 72,443

7 Claims. (Cl. 214—18.3)

1

This invention relates to stoker mechanisms and more particularly to overfeed stokers of the sprinkler type. Such stoker mechanisms are also sometimes called spreader stokers. The term "sprinkler" will be used herein and will be understood to include both the sprinkler or spreader types, however designated.

During the operation of overfeed sprinkler stokers the fuel is delivered intermittently by an intermittently operated feeding mechanism, and from this the coal falls upon a rotating element which strikes the falling coal and impels or "sprinkles" it into the combustion space where the lighter particles are burned in suspension, the heavier particles falling onto a grate where combustion is completed.

Various intermittent coal feeding mechanisms have been provided, one type being exemplified by my prior Patent No. 2,163,825. In this patent the fuel is delivered from a hopper or feed spout to a feed plate where the fuel is periodically shoved forwardly toward the furnace by means of a reciprocating feed shoe and a quantity of coal, which is thus measured off and moved by each forward motion of the feed shoes, is pushed forward and shoved off the delivery end of the feed plate for each working stroke of the feed mechanism. As the fuel falls it is engaged by a bladed rotor arranged below the delivery end of the feed plate, and since the rotor is revolving at relatively high speed, the rotor blades strike the falling particles of fuel and impel or "sprinkle" them into the combustion space where the particles are burned, partly in suspension and partly on the grate at the bottom of the combustion zone. Usually the finer particles burn in suspension and the heavier particles, which may ignite and partially burn before they fall onto the grate, are then consumed on the grate below. In some instances a chain or traveling grate is used in a furnace of this type and always a thin fuel bed is used. This type of stoker mechanism is highly responsive to load fluctuation as the combustion rate can be changed widely and rapidly.

Other types of mechanisms are also used for intermittently moving forward measured (metered) quantities of fuel, which is then sprinkled by the revolving rotor situated below the feed device. In another form of such mechanism the coal is moved forward periodically and in somewhat metered amounts by a small feed conveyor (belt or chain type) that is actuated intermittently, step-by-step, the coal being delivered off the end of the conveyor and onto the revolving rotor for the sprinkling operation.

Thus, in all stokers of this character there is a

2

combination of intermittent feed or measured amounts of coal onto the sprinkler element. The average feed rate is varied, either by changing the frequency of stroke or movement of the feed means or by changing the length of the stroke or distance of movement of feed belt or other feeding means for each feeding movement of the device.

In the operation of sprinkler stoker mechanisms of the aforesaid type the fuel does not fall constantly upon the rotor but is delivered to the rotor intermittently due to the reciprocating motion of the feed shoe on the feed plate or intermittent forward motion of feed conveyor or other feed means. Accordingly, the rotor delivers fuel particles into the furnace in a cyclic manner with practically all the coal being delivered on the forward movement of the intermittent feeding mechanism and practically none during the pause or back stroke of the feeding mechanism preparatory to obtaining a fresh charge of fuel for the next cycle. Therefore, in the operation of sprinkler stoker mechanisms, whether of the feed shoe or conveyor feed type, there is an appreciable period of time in each feeding cycle (40% to 50%) during which fuel is not being fed, and during these periods of minimum feeding there is little or no coal impelled into the furnace. This intermittent feeding of fuel into the furnace causes fluctuation in the furnace draft, puffing out of the furnace, difficulty with draft control apparatus and, to some degree, unfavorable combustion efficiency which arises out of the following circumstance.

In the operation of all spreader stokers the coal, consisting of fine and coarse particles in a variety of sizes, is impelled into the combustion space. Ignition is rapid, almost to the point of explosion, and fine particles are consumed before they can fall to the grate. Any particle which is not completely burned during its fall through the combustion space burns on the grate. As explained above, the coal feed is intermittent, being usually about 25 to 50 strokes or feeding motions per minute with a pause (or a condition of non-feeding) between each feeding motion. Integrated, there is a condition of coal feeding for roughly 50% of the time and a condition of no feeding for the remainder of the time. Yet the combustion air is fed at a constant rate.

Insofar as concerns the coarse coal on the grate, a constant feed of combustion air is no disadvantage, but to the extent that the coal

55 may contain fines which burn in suspension and

before falling on the grate, constant feed of air for combustion has offered the disadvantage that if the combustion air is sufficient in amount to effect complete combustion of the fines in suspension while they are being fed, the same rate of feed of air for combustion represents an excess when no (fines) coal is being fed. This has the net effect of increasing the average excess air passing through the furnace and a consequent decrease in CO_2 content in the flue gases. There is presently available no practical way of varying combustion cyclically to compensate for the cyclical feed of the fuel. There has likewise been no practical way, prior to this invention, for attaining a reasonably constant rate of fuel injection into the furnace with sprinkler stokers.

It may be stated parenthetically that intermittent feed mechanisms are universally used in sprinkler feed stokers because of their many advantages in simple design, cheap construction and reasonably good operation. They can be constructed so as to afford accurate feeding over a wide range of feeding rates, while still being driven by small horsepower alternating current motors of conventional design. The design and construction of accurate continuous-feed coal feeding devices capable of wide variations in rate of feed is difficult and costly and such few devices that have been experimented with have not been satisfactory from the standpoint of operation. Therefore, so far as is known, they have never been used in commercial installations.

It is one of the broader objects of the present invention to provide an improved cyclic sprinkler stoker mechanism wherein the fuel is delivered to the furnace in accurately controlled amounts and at substantially constant rate, throughout the complete cycle to the rotating distributing mechanism.

It is a further object of the invention to provide an improved overfeed stoker of the sprinkler type wherein granular fuel is fed intermittently and yet delivered at a substantially constant rate throughout the cycle of operation of the feed mechanism to the rotor mechanism of the stoker for distribution thereby into the combustion space.

It is another object of the invention to provide an improved sprinkler overfeed stoker mechanism wherein the fuel is fed intermittently in accurate, yet selectively variable amounts by an oscillating mechanism on a feed plate and the feed plate is deflected or a part thereof oscillated during a portion of the oscillating cycle of the feed mechanism so as to provide a nearly uniform delivery of the granular fuel from the feed plate to the rotating element of the sprinkler mechanism.

It is a further object of the invention to provide an improved sprinkler stoker mechanism having a fuel feed plate provided with a deflectable, slideable, or otherwise movable tip and an oscillatory feed shoe interconnected therewith for changing the position of the tip to cause fuel to be delivered therefrom during those portions of the oscillatory action of the feed shoe when no fuel would normally be delivered by the latter.

Other and further objects of the invention include the provision of specific mechanisms for accomplishing the aforesaid results and also include those objects inherent in the apparatus herein illustrated, described and claimed.

The invention is illustrated with reference to the drawings in which corresponding numerals refer to the same parts and in which

Figure 1 is a side elevational view, partly in section, of one illustrative embodiment of the invention showing the stoker mechanism and a section of the boiler or furnace wall to which the stoker mechanism is applied. Figure 1 shows the intermittent feed mechanism at the completion of a feeding stroke;

Figure 2 corresponds to the apparatus shown in Figure 1 and is an enlarged fragmentary side sectional view of a portion of the apparatus illustrating the apparatus at an intermediate position during its cycle of operation;

Figure 3 corresponds to Figures 1 and 2 and is also an enlarged fragmentary side sectional view showing the apparatus at the beginning of its cycle of operation;

Figure 4 is a fragmentary side elevational view, partly in section, showing another illustrative embodiment of the invention;

Figure 5 is a fragmentary sectional view taken along the line and in the direction of arrows 5-5 showing the tip plate adjustment screw of the apparatus shown in Figure 4;

Figure 6 is a fragmentary side elevational view, partly in section, of a further illustrative form of the invention;

Figure 7 is a vertical side elevational view, partly in section, showing another illustrative embodiment of the invention;

Figure 8 is a fragmentary side elevational view showing another slightly modified form of apparatus.

The illustrative embodiment of the invention shown in Figures 1, 2 and 3 is a stoker mechanism of the oscillating feed-shoe type of the same basic character as illustrated in my Patent No. 2,163,825, to which reference is made for certain details of the mechanism. In Figures 1-3 emphasis is given to those portions of the apparatus which are modified as compared with the stoker illustrated in Patent No. 2,163,825 and reference is made to that patent for many details of the apparatus that are not illustrated in the instant disclosure, these details being important to the apparatus but for simplicity omitted herein.

Referring to Figure 1 there is illustrated a furnace or boiler generally designated 1 having a front wall generally designated 2 and a combustion space 4 defined by the ignition arch 5 and the front wall 2. The brickwork forming the arch 5 encloses an air duct 7 to which there are attached a plurality of air inlet tuyères 6 by means of which overfire combustion air is delivered to the combustion space immediately adjacent to the in-flowing delivery of fuel through the fuel aperture 8.

Upon the front wall 2 of the boiler or furnace there is mounted the main stoker frame generally designated 12 which is provided with a mounting flange 11 that is attached to the front wall 2 of the furnace or boiler by means of bolts 9. The lower portion of the frame 12 is provided with an access door 13 that is held in place by a suitable latch 14.

At the lower part of the stoker frame 12 there is a bladed sprinkler rotor generally designated 17 which rotates continuously and at a relatively high speed for striking the fuel particles 70 and impelling them through the fuel inlet 8 and into the combustion space 4. The rotor is contained within a partial cylindrical space defined by a half-cylindrical cover member 15 which is removably attached to the lower portion of the 75 stoker frame by a plurality of cap screws. The

space in which the bladed rotor 17 is positioned is also partially defined by the middle portion 10 of the stoker main frame. The direction of rotation of the rotor 17 is shown by the arrow shown adjacent its periphery. In rotating, the blades of the rotor engage and impel the fuel particles through opening 8 and into the combustion zone.

The details of construction of rotor 17 are described in my Patent No. 2,163,825 wherein it is stated that the rotor 17 may be composed of one or a plurality of segments mounted upon a tubular shaft 22 which is supported in spaced relation in respect to shaft 18 by suitable collars not herein illustrated. The rotor 17, tubular shaft 22 and shaft 18 all rotate as a unit, the space between the tubular member 22 and the shaft 18 serving to restrict heat communication from the rotor 17 to the shaft 18. The shaft is thus spared from operating at high temperatures. The mechanism for continuously revolving the rotor 17 in the direction shown need not be specifically described herein since it is described in detail in my patent referred to above.

Upon the front of the stoker mechanism there is provided a fuel hopper generally designated 31 that is mounted upon a bracket 32 attached to the main frame 12 of the stoker mechanism. The bracket 32 includes an integral bar 36 and an integral apertured guide 39 which serve jointly to support the feed plate generally designated 35. The feed plate is movable toward and from the boiler wall. For this purpose this is an integral downwardly extending lug 44 which is threaded on the inside to receive the threaded portions 37 of an adjustment bolt 46. The adjustment bolt is provided with a collar 42 suitably attached to the bolt so that it rotates with the bolt. The collar 42 is positioned in a notch in the guide 39 and by this means the bolt 46 is permitted to rotate and yet is held from moving endwise. Accordingly, by rotating the bolt 46 the lug 44 is moved longitudinally of the bolt and in this manner the feed plate 35 may be moved back and forth toward and away from the boiler or furnace wall, and hence the fuel delivery end of the feed plate may be adjustably positioned in respect to the rotor so as to vary the point of delivery of fuel to the rotor.

At the rear end of the bolt 46 there is provided a square sleeve 45 which is positioned between the head on bolt 46 and the adjacent wall of the guide portion 39. The sleeve is loosely mounted upon the bolt and accordingly, as the bolt 46 is turned, the sleeve 45 does not turn, being held from rotation by its square configuration which abuts against the lower surface of the feed plate 35. An indicating finger 47 is attached to the rear part of the feed plate and a plurality of indicia are placed upon the square sleeve 45 so that the operator may know the fore and aft adjustment of the feed plate.

The feed plate 35 may be mounted horizontally, although it can also be mounted at a slight angle, as shown in my patent above referred to. Upon the feed plate there is mounted an oscillatory feed shoe generally designated 48 which has a plurality of vertical walls 49 and 51 and interconnecting top surfaces. The walls 49 and 51 are connected by the portion 52 which forms a step-down from the top of the feed shoe. The lower and rear portion of the hopper 31 is provided with a seal plate 73 having a flexible sealing member 72 attached thereto by screws 74. The position of the seal is adjusted so that it slides upon

the smooth upper surface of the feed shoe, and thereby as the shoe is oscillated, as hereinafter described, the fuel is prevented from being pulled back as the shoe moves backwardly. The base 5 of the front wall 49 of the shoe slides directly upon the feed plate 35.

Oscillatory motion of the feed shoe is imparted by means of a plurality of forked rocker arms 55 that are attached to an oscillating shaft 53. The 10 rocker arms are rotated back and forth in the direction of the double arrow shown adjacent the shaft 53 due to the oscillatory motion of the shaft, and accordingly the upper ends 57 of the arms 55 are likewise moved back and forth in the direction of the double arrows shown adjacent to the upper ends. The upper ends 57 of the forked arms 55 are attached by links 56 to the shoe 48 and therefore as the arms 55 are moved back and forth, the shoe 48 is likewise moved back and forth and serves at each oscillation backwardly (away from the rotor 17) to receive the downwardly moving flow of granular fuel from the hopper 31 and on each forward movement (toward the rotor and boiler or furnace), the fuel 20 is shoved along the feed plate 35, as shown in Figure 1, toward the delivery end of the feed plate, whence it falls upon rotor 17.

The forward end 38 of the feed plate is provided with a movable tip 165 extending entirely 30 across the front edge of the feed plate.

In the construction, as shown in Figures 1, 2 and 3, the tip plate, which is generally designated 165, is supported by a plurality of bell crank levers 168, these in turn being pivotally mounted 35 on pins 169 that are carried by brackets on the under side of the feed plate 38. The bell crank levers 168 have downwardly extending portions 171 to which there is pivotally attached one end of the links 172 which extend back to the oscillating arms 55 to which the links 172 are also pivotally attached at 173. The length of the links 172 is made adjustable so that when the forked oscillating arms 55 are in the maximum forward position, as shown in Figure 1, the bell crank 40 levers 168 are held in such a position that the tip plate 165 is in a plane approximately parallel to the feed plates 38 when the feed plate adjustment 46-47 is in its middle position. In 45 this position the tip plate just underlies the feed plate, as shown in Figure 1. As the oscillating forked arms 55 move rearwardly and hence draw the feed shoe 48 rearwardly, to the position shown in Figure 2, the links 172 are moved rearwardly and this causes the bell crank levers 168 to be moved, and this causes the tip plate 165 to be tilted downwardly to an intermediate position shown in Figure 2. Accordingly, approximately one-quarter of the fuel fed by the shoe on its forward stroke, which had up 50 to that time been reposing on the end 38 of the feed plate and tip plate 165, is permitted to slide down the tip plate 165, due to the downward tipping action of the tip plate which changes the forward point of support of the coal. 55 The coal will immediately assume its natural angle of repose of 45 degrees and the change in position of forward support of the coal will permit about one-quarter of the fed amount to slide onto the rotor.

As the motion of the forked oscillating arms 55 is continued to the position shown in Figure 3 and as the feed shoe 48 is thereby drawn to its rearmost position, the links 172 are likewise drawn rearwardly and in so doing moves the oscillating bell crank levers 168 to their most

downwardly extending position, thereby causing the tip plate 165 to be tipped downwardly at its most extreme angle and thus the fuel which had been on the tip plate 165 and feed plate 35 is permitted completely to slide off the end of the tip plate 165 and onto the rotor 17 where the distribution of the fuel is achieved by the rapid rotation of the bladed rotor. As the mechanism continues through its cycle of operation the forked oscillating links 55 again move toward the rotor 17 and hence moves the feed shoe 48 in that direction and through the action of rods 172 and the oscillating bell crank levers 168, gradually lift the tip plate 165 from the position shown in Figure 3 through the position shown in Figure 2 to the position shown in Figure 1. The forward movement of the feed shoe 48 pushes enough fuel forwardly so that approximately half of the fuel is caused to be discharged off the end of the tip plate 165 on the forward movement of the feed shoe, even though that plate is, during this portion of the cycle of operation, being lifted to its substantially horizontal position of Figure 1. Accordingly, as the apparatus continues its cycles of operation each forward motion of the feed shoe 48 pushes enough fuel forwardly so that approximately one-half of the metered slug of fuel is discharged off the tip plate 165 while the feed shoe 48 is moving forwardly and even though the tip plate 165 is then being elevated, and then as the oscillation continues and the feed shoe 48 begins to retract rearwardly away from the rotor (during which the normal spreader stoker does not deliver any appreciable amount of fuel), the downwardly tipping action of the tip plate 165 dumps an approximately equal amount (one-half) of the fed amount of fuel off the end of the combined feed plate 38-165 and thus continues the delivery of the fuel during this portion of the cycle (when normally there is no coal fed).

The amount of coal fed during the cycle of operation is illustrated by the dotted lines in Figure 3, which in full lines shows the feed shoe and tip plate at the beginning of the feed stroke and in dotted lines shows these members at the end of the feed stroke (corresponding to the Figure 1 position). When in the full line position (of Figure 3) the tip plate is tilted and the approximate one-half portion of coal (portion A-B-D-C) of the coal which had been fed up and which had rested on the tip plate (when raised to the dotted line position) has now slid off. Hence, the coal face is at line C-D and the amount fed on the next stroke is the metered slug C-D-H-G, which is shaded. The portion G-H-J merely is part of the mass of coal in the system. Then, as the cycle progresses to the Figure 2 position, the tip plate has risen somewhat and the shoe 48 has already forced the slug C-D-H-G forward and some of it has slipped off the feed plate leaving G-H-Y-X. Finally as the mechanism reaches the Figure 1 position, the portion E-F-H-G is moved up so that it occupies the position at the exposed end of the tip plate (corresponding to portion A-B-D-C of Figure 3) and this approximate one-half portion of the coal fed on that forward stroke is ready to be dumped, during the ensuing backstroke, all as previously described. While the feed is not absolutely constant throughout the complete cycle, it can be seen that at least one-half (or approximately one-half) of the amount of coal fed on the complete forward stroke is dumped during the forward

stroke and approximately one-half is dumped on the return stroke. While the coal falling off the end of the tip plate does not do so at an absolutely constant rate during each half cycle, the discharge (pushing or sliding) does occupy an appreciable time interval and there is accordingly almost no time during the entire cycle of operation when the delivery is not substantially constant. The delivery is more in the manner of a slightly undulating delivery rate throughout the whole cycle, and the apparatus accordingly affords many advantages over stokers previously available, wherein there is a condition of non-delivery for at least half of each cycle.

The average angularity of the tip plate is slightly varied as the plate 35 is moved back and forth, but this is not a disadvantage for the free edge of the plate may thus be varied in position with reference to the center line of rotor 17 for varying the position at which the fuel particles are engaged and hence the direction in which they are impelled. If desired, the tip plate pivot pins holding brackets 168 may be mounted on portion 170 of the stoker enclosure frame so as not to be subject to variation in angle of tilt as plate 35 is adjusted but at the expense of not being able to adjust the free edge of the tip plate relative to the rotor.

The stoker mechanism also includes a feed gate generally designated 79 which is pivotally supported upon the shaft 82, the latter being supported at the end of the stoker mechanism frame. The feed gate includes air inlet ports 88 through which some over-fire air is delivered into the combustion space of the furnace. The feed gate 79 normally resides in the position shown in full lines in Figure 1 but is free to oscillate upwardly against its own weight and about the pivot shaft support 82, in the event enlarged objects, such as tramp iron or the like, should be pushed forwardly against it by the oscillating feed shoes 48. The thus raised position of the feed gate is shown in dotted lines in Figure 3.

The mechanism for oscillating the shaft 53 and for continuously rotating the rotor shaft 18 are as described in my patent aforesaid and therefore need not be repeated here.

In Figure 4 there is illustrated another exemplary form of the invention wherein the tip plate is mounted so as to be slidable relative to the feed plate, rather than pivoted for tilting action as in Figure 1-3. Thus, in Figure 4 the feed shoe 48 is arranged for oscillatory back-and-forth movement and is driven by link 56 connected by a pivotal connection to the upper end 57 of the oscillating rocker arm 175. The feed plate 35 is in this form of the invention constructed so that it is adjustable toward and away from the furnace by means of the adjustment screw 46-37, as in Figures 1-3. At the furnace end 38 of the feed plate 35 there is mounted a sliding tip plate 176 which is supported by guide rails 177 at opposite sides of the feed plate 35, the rails 177 being below the surface of the feed plate 35. The slidable tip plate 176 is provided with one or more downwardly extending lugs 178 to which there is pivoted the clevis 179 of an actuating link generally designated 180. The actuating link 180 is pivoted in the clevis 179, being supported therein against longitudinal movement by a pair of collars 188 that are fastened to the link so as to hold the clevis from endwise movement and yet permit rotation of the link 180. At the right end of the link 180,

as shown in Figures 4 and 5, there is a threaded portion 181 terminating in a hand wheel 187. The threaded portion 181 passes through a threaded connector 182 which has a pivot shank 183 passing through the oscillatory lever 175, the shank 183 being held in place on the oscillating lever arm 175 by means of a collar 184 that is pinned or otherwise suitably attached so that the entire connector 182-183-184 is free to pivot in the oscillating lever 175 as the lever oscillates back and forth in moving the feed shoe. By means of this arrangement, which is shown in detail in Figure 5, the position of the sliding tip plate 176 may be adjusted with reference to the feed shoe 48.

It will be noted that the point of pivotal connection of the member 182 to the oscillating lever 175 is about midway between the pivot shaft 185 upon which the oscillating lever 175 is mounted. Accordingly, as the lever 175 oscillates back and forth and moves the shoe 48 back and forth on the feed plate 35, the lever 175 through the link 180 also imparts a back-and-forth sliding movement of the sliding tip plate 176, but the total distance (back and forth) through which the tip plate moves is approximately one-half of the total distance moved by the feed shoe 48 due to the fact that the distance from the center of the pivot shaft 185 to the center of the member 182 is approximately one-half as far as from the pivot shaft 185 to the pin 57' by which link 56 is attached to the upper end 57 of the oscillating lever 175. Accordingly, as the feed shoe 48 moves forwardly (and therefore moves a measured amount of coal forwardly), the tip plate 176 is also moving forwardly but at a rate approximately half as fast. Therefore, the coal which is being pushed forwardly overtakes the front edge 176' of the sliding tip plate and some of the coal, approximately one-half thereof, is shoved off the end of the plate and thereby falls onto the rotating spreader 17. As the feed shoe 48 reaches its position closest to the furnace (and closest to the rotating spreader 17) the coal that is deposited on the exposed upper surface of the tip plate 176 is left there preparatory to being dumped as the tip plate is then drawn rearwardly during the reverse half cycle of the oscillating movement of the mechanism. Accordingly, approximately one-half of the coal is dumped on the reverse half of the cycle and approximately one-half is dumped on the forward half of the cycle, thus distributing the coal relatively uniformly upon the revolving spreader rotor 17 during the complete cycle of back and forth movement of the feed shoe 48.

In Figure 6 there is illustrated another exemplary form of the invention similar to that shown in Figures 4 and 5 but simplified in that the link generally designated 190, which corresponds to the link 180 of Figures 4-5, is made non-adjustable and is fitted so that it protrudes through openings 191 and 192 in the walls 51 and 49 of the feed shoe and then extends outwardly to the left and above the feed plate 35 and is connected to an upwardly extending lug 193 which extends upwardly from the upper surface of the slidable tip plate 194. The plate 194 is mounted for sliding motion back and forth in parallel guides 177 on the lower side of the feed plate 35 in the same manner as shown in Figure 4, but in this instance the lug for oscillating the sliding tip 194 protrudes upwardly and to it there is pivotally attached the clevis 195 on the forward end

of the link 190. The rear end of the link 190 is likewise provided with a clevis 196 which is pivotally attached at 197 to the oscillating lever 189. The point of pivotal attachment 197 in Figure 6, and the point of pivotal attachment of the member 182 of Figure 4 may be varied up and down in any design so as to adjust the relative movement of tip plate and feed shoe and hence the amounts of coal delivered during each half of the cycle. The clevis 195 is preferably made with a knife-edge stern 198 so that it cuts through the coal on its rear stroke and a slot is provided in the feed plate 135 at 199 so as to provide a space in which the lug 193 is free to operate. The operation of the device shown in Figure 6 is substantially identical with that shown in Figures 4-5.

In Figure 7 there is shown a further illustrative form of the invention wherein the fuel is fed step-by-step in measured amounts by means of a small conveyor from which it is delivered onto the revolving spreader or sprinkler rotor in a manner similar to the apparatus previously described. In the device shown in Figure 7 the stoker frame 200 is provided with a coal feed opening defined by the water cooled casting 201 which at its lower side 202 forms a part of the partial cylindrical chamber 203 in which the spreader rotor 204 revolves. The outer portion of the chamber 203 is formed by the frame plate 205. Upon the frame 200 there is mounted a hopper 206 which is supported by the auxiliary frame member 207. The bottom of the hopper empties through a delivery opening 208 upon a conveyor mechanism generally designated 209 which is mounted between side wall frame plates 210. The conveyor mechanism is provided with a table portion 211 upon which the upper portion of the conveyor belt 212 travels, the belt moving toward the furnace at its upper surface and thence over the front conveyor roller 213 and thence away from the furnace at its lower course of travel until it reaches the conveyor drive roll 214. The conveyor drive roll is mounted upon the shafts 215 which are driven by a ratchet wheel 216. Freely pivoted upon one of the shafts 215 there is also provided an oscillating lever 217 which is moved back and forth by means of the link 218. Member 218 moves back and forth in the direction of the double headed arrow 219 being driven by a mechanism not illustrated, such as the revolving crankshaft driven from a suitable power source. The oscillating lever 217 thus oscillates back and forth on the shaft 215, as shown by double arrow 219. The oscillating lever 217 is provided with a pawl 220 which engages the teeth of the ratchet wheel 216 causing the wheel to move in the direction of arrow 221 when the upper end of the lever 217 moves towards the furnace and ratcheting back over the teeth (and consequently permitting the conveyor drive ratchet 216 to remain still) when the upper end of the lever 217 moves away from the furnace. Thus, the conveyor belt 212 is caused to move step-by-step and the upper surface thereof accordingly carries the coal C or other granular fuel forward toward the delivery end of the conveyor at roll 213 in a step-by-step motion, a measured amount of coal being thus propelled for each step-by-step movement of the conveyor. If desired, the ratchet drive mechanism comprising ratchet wheel 216, oscillating lever and link 217 and 218 and pawl 220 can be mounted so as to drive the front roller 213 rather than the rear roller 214. To do this it is only necessary to connect ratchet wheel 216 to the

11

shaft on which the front roller 213 is mounted. Lever 233 is then connected appropriately so that the plate 230 is raised as the coal is fed.

In previous apparatus of this sort the coal was permitted to fall off the conveyor directly onto a revolving rotor 204 to be spread thereby, and all of the coal was spread during the feeding portion of the cycle and none was spread during the non-feeding portion of the cycle. In the instant embodiment of the invention this apparatus is modified by the provision of an oscillating tip plate 230 which is pivoted on shaft 231 for oscillatory movement up and down in the direction of the double headed arrow 232. The shaft 231 is provided with a lever 233, at the upper end of which there is pivotally attached one end of an operating link 234. The link 234 has its rearward end 235 pivotally connected to a downwardly extending portion 236 of the lever 217. As the lever 217 is moved toward the furnace and thus drives the conveyor belt so as to cause the latter to carry a measured quantity of coal towards the delivery end of the conveyor, the lower end 236 of the lever moves away from the furnace, thus pulling on the link 234 and causing the lever 233 to be moved clockwise about the pivot shaft 231 which accordingly causes the tip plate 230 to be moved clockwise or, stated otherwise, to be tilted upwardly so as to support some of the coal that is delivered off the conveyor. Then as the upper end of the lever 217 moves away from the furnace and the pawl 220 ratchets back freely over the teeth of the ratchet gear 216, during which the conveyor 212 is not propelled and no fuel moved thereby, the lower end 236 of the lever 217 moves clockwise (towards the furnace) thus permitting the links 234 likewise to move towards the furnace causing lever 233 to move counterclockwise and thus causing the plate 230 to be tilted downwardly. Accordingly, that portion of the coal which has been deposited on the plate 230 on the feeding stroke of the conveyor is now permitted to slide off the plate and to be dropped onto the revolving distribution roller 204. Thus, during that portion of the cycle of operation when, in accordance with prior practice, there is normally no coal fed to the furnace, in accordance with the instant invention, coal is delivered off the tip plate onto the revolving roller, thus substantially unifying the delivery of coal from the oscillating feed mechanism.

If desired, the sliding tip plates 116 or 194 of Figure 4 or 6, respectively, may be substituted for the tilting tip plate 230 of Figure 7. To do this a horizontal stationary guide 240, similar to plate 35 and slides 171 of Figures 4 and 6 except that it is made a part of the stoker frame member 205, is provided immediately under roller 213 of the Figure 7 device and fitted with a vertical fin 241 reaching up to the under course of belt 212. This forms a slot at 245. A horizontal or nearly horizontal sliding plate is then mounted on this guide device for back and forth motion. The slide plate is then coupled by a link 243, which in such case is pivoted on lever 217 at point 244 above shaft 215, so the sliding tip plate will be projected out and hence catch and hold part of the coal as it is fed off the end of belt 212 during the feeding portion of the cycle, and thereafter when the sliding plate is retracted during the back stroke of lever 217, it will spill the coal that was temporarily held.

As many apparently widely different embodiments of this invention may be made without departing from the spirit and scope thereof, it is

12

to be understood that I do not limit myself to the specific embodiments herein.

What I claim is:

1. A sprinkler stoker mechanism comprising fuel supply means, a feed plate on which the fuel is delivered and along which said fuel is movable, a rotor horizontally situated below said supply means and of about the width of said plate for impelling into a combustion space granular fuel falling downwardly off of an edge of said plate onto said rotor, means movable along a fraction of the length of said plate towards said edge for moving towards said edge successive portions of fuel during successive time intervals spaced by periods of non-delivery, and for dropping said fuel off of said edge and along the entire width of said rotor, said fuel being moved from said supply means to said rotor to be impelled thereby and means for intercepting a part of each successive portion of fuel and for delivering said intercepted parts across the entire width of said rotor during said spaced periods of non-delivery, said means for intercepting comprising a tilting plate mounted adjacent the delivery end of said feed plate.

2. An overfeed sprinkler stoker mechanism comprising a frame, a fuel supply means for delivering granular fuel downwardly, a feed plate below the fuel supply means for receiving the fuel, feed means and means for moving said feed means periodically on said plate for pushing the fuel periodically along the plate toward a delivery end thereof, a tip plate adjacent the delivery end of said feed plate, means mounting the tip plate for oscillation about a substantially horizontal axis and means connecting the tip plate and feed means for moving the tip plate downwardly as the feed shoe means is moved away from the delivery end of the feed plate, and a rotor mechanism positioned below the tip plate for engaging and distributing the fuel as it falls downwardly off said tip plate.

3. In an overfeed sprinkler stoker mechanism a frame having a fuel delivery aperture therein, a rotor mounted adjacent said aperture and means for rotating said rotor for engaging particles of solid fuel and impelling them through said aperture, a feed plate positioned over said rotor and having a delivery end above the rotor, fuel supply means positioned above said feed plate, the improvement comprising a tilttable end adjacent the delivery end of the feed plate, a feed shoe mounted on said feed plate, means for oscillating the feed shoe back and forth in a direction to push the fuel from the fuel supply means towards said tilttable end, and means for tilting said end downwardly as the feed shoe is moved away from said tilttable end moving said tilttable plate upwardly when the feed shoe moves towards said tilttable end.

4. An overfeed sprinkler stoker mechanism including a frame, said frame being formed with a fuel delivery aperture therein, a bladed rotor positioned adjacent said aperture for sprinkling fuel therethrough into a combustion space, means for rotating said rotor, a fuel feed plate positioned above the bladed rotor and solid fuel delivery means above the plate for delivering solid fuel in particle form downwardly onto said plate, feed shoe means positioned on the feed plate in the path of downward fuel flow, means for oscillating said feed shoe means back and forth to push fuel towards an edge of the feed plate that is above said rotor, a tip portion adjacent said edge of the feed plate and forming a continua-

tion of said plate, said tip portion being above said rotor, means mounting said tip portion for oscillatory tipping about a substantially horizontal axis and means for moving the tip portion downwardly as the feed shoes move back to receive a fresh charge of fuel and for moving the tip portion upwardly as the feed shoe means is moved towards said tip portion.

5. An overfeed sprinkler stoker mechanism having a substantially upright frame, said frame being provided with a fuel delivery aperture therein, a bladed rotor mounted for rotation about a substantially horizontal axis positioned adjacent said aperture for impelling solid fuel particles therethrough, means for revolving said rotor, a fuel feed plate positioned substantially horizontally and having a delivery edge generally parallel to the axis of rotation of said bladed rotor and above the same, a fuel delivery chute positioned above the fuel feed plate for delivering granular fuel downwardly thereon, feed shoe means mounted on the feed plate and means for oscillating the feed shoe means back and forth from a position where it receives the fuel to a position where the fuel is pushed towards the delivery edge of the feed plate and onto the rotor, an auxiliary delivery tip for said feed plate, means mounting said delivery tip adjacent the delivery edge of said feed plate for oscillation back and forth between a position in which it intercepts fuel delivered to the delivery edge of the feed plate and a position in which it spills fuel thus intercepted, and means for oscillating the tip to intercepting position as the feed shoe is moved towards said delivery edge of the feed plate and for moving the tip to spilling position as said feed shoe is moved away from said delivery edge.

6. An overfeed sprinkler stoker mechanism comprising an upright frame wall having a central fuel delivery aperture therein, a partial cylindrical housing on said frame and a bladed fuel sprinkler rotor mounted about a generally horizontal axis in said housing, said housing being open to the fuel delivery aperture, means for revolving said rotor, a fuel feed plate mounted above said rotor in a generally horizontal position, said fuel feed plate having a delivery edge above and generally parallel to the axis of rotation of said rotor, a fuel chute for delivering granulated fuel downwardly on said feed plate, feed shoe means slidable back and forth on said plate, means for oscillating said feed shoe means back and forth on said feed plate in a direction to

push the granular fuel toward said delivery edge and then to withdraw said feed shoe means from the delivery edge of said feed plate, auxiliary delivery tip means adjacent and underlying the delivery edge of the feed plate, means mounting said delivery tip means for oscillation from a position in which it forms a fuel supporting extension of the feed plate to a position in which it spills fuel supported thereon, and means connecting said delivery tip means for oscillating said delivery tip means to spilling position as said feed shoe is moved away from said delivery tip means and for oscillating said delivery tip means to fuel supporting position as said feed shoe means is moved towards said delivery tip means.

7. A sprinkler stoker mechanism comprising fuel supply means, a feed plate on which the fuel is delivered and along which said fuel is movable, a rotor horizontally situated below said supply means and of about the width of said plate for impelling into a combustion space granular fuel falling downwardly off of an edge of said plate onto said rotor, means movable along a fraction of the length of said plate towards said edge for moving towards said edge successive portions of fuel during successive time intervals spaced by periods of non-delivery and for dropping said fuel off of said edge and along the entire width of said rotor, said fuel being moved from said supply means to said rotor to be impelled thereby and means for intercepting a part of each successive portion of fuel and for delivering said intercepted parts across the entire width of said rotor during said spaced periods of non-delivery, said means for moving successive portions includes a feed plate having a delivery end and a feed shoe mounted for oscillation thereon for moving the fuel in successive portions to said delivery end, said means for intercepting comprising a tilting plate mounted adjacent the delivery end of said feed plate.
